HYDRAULIC INSTALLATION

Arnold Pfau, Milwaukee, Wis., assignor to Allis-Chalmers Manufacturing Company, Milwaukee, Wis., a Corporation of Delaware

Application May 18, 1928. Serial No. 278,886

15 Claims. (Cl. 137—158)

This invention relates in general to power installations and it has particular relation to hydroelectric power installations where the hydraulic machine is operative under or against a widely varying head.

Turbines of hydraulic power plants which are subject to a highly variable head such, for instance, as certain streams or the high and low tide of the ocean, suffer a considerable loss in the power developed. This is particularly the case with very low heads where even a slight change in the head amounts to quite a considerable portion of the full normal head. For instance, if the normal net head is 4.5 meters, the highest head 6 meters, and the lowest head two meters, the total average amounts to 4 meters or 88.8% of the normal head.

It is well known that the number of revolutions or speed of a turbine varies with the square root of the net head. For instance, if the revolutions are 100 per minute on the 16 meters head, it is 100 divided by $\sqrt{2}$, or about 71 revolutions under 8 meters, and it is 100 divided by $\sqrt{4}$, or 50 revolutions, that is, half of the former amount, when the head has dropped to $\frac{1}{4}$ of the maximum head.

If the turbine is directly connected to an alternating current generator, it should always operate at the same number of revolutions, otherwise the number of periods or frequency of the current would change, and this would render parallel operation with other generators impossible. Therefore, if a turbine were normally designed for 100 revolutions under 16 meters net head, it would have to develop under 4 meters head, not 50 revolutions, but twice as much, that is, 100 revolutions, in order to produce current of the proper number of periods or frequency. A turbine operating at a speed which is 100 per cent higher than normal, however, shows, such unfavorable hydraulic efficiencies that it becomes uncommercial to still use a turbine for such operating conditions.

The speed of the generator could be maintained normal by using in steps belt drives or similar devices with proper transmission ratios. This arrangement, however, is impossible where large units are used and particularly when the turbine and generator are directly coupled, which is the most favorable mechanical solution.

The power developed by the turbine is even more sensitively affected by a change in the net head; first, on account of the head itself, second, on account of the discharge capacity. It is well known that

55

$$Q_1:Q_2 = \sqrt{H_1}:\sqrt{H_2}, \text{ where}$$

Q_1 =quantity of water under the head H_1 ,

Q_2 =quantity of water under the head H_2 ,

and

60

$$HP_1:HP_2 = H_1:\sqrt{H_1}H_2:\sqrt{H_2} \text{ where}$$

HP_1 =power at head H_1 ,

HP_2 =power at head H_2 .

The capacity or power of the turbine, however, is also subjected to a variation in the efficiency of the turbine, and this deviates more from the best value as the number of revolutions or speed is greater or less than the normal speed.

65

Therefore, if the power or capacity, for instance, under 16 meters net head, is 4000 HP, then it is, according to the above formulae, only 500 HP under 4 meters, and this does not as yet consider the loss of power due to reduced efficiency. Now, if the turbine must maintain its 100 revolutions, it would have to run twice as fast as is necessary in order to maintain its normal efficiency. Therefore, the efficiency will drop to such extent that nothing will be left of the 500 HP. In other words, the turbine will produce no power and, therefore, represents a dead capital investment.

75

The invention of the present application is concerned with the provision of an improved power system, for the economical utilization of a power source of relatively widely varying available head or pressure, and it more particularly involves the use of a plurality of power units of such individual design as to capacity and normal operating head or pressure under which the units operate, each at its predetermined desired speed, as to insure operation of the system under different heads or pressures under conditions of maximum efficiency. And the present invention is further concerned with features of automatic control of a system involving a plurality of turbines driving or supplying power to a common load so as to insure operation of the load, such as an alternating current generator, at a controlled speed throughout full variation in the head independently of whether one or more or all of the turbines supply power to the load, es-

80

95

100

pecially such operation as is desired to secure economical operation at high overall efficiency of the system. As a further feature, the control of a system, particularly a hydro-electric system, 5 of the character described, as to the necessary changes or operations required to accommodate for the difference in head to which the turbines are subjected, or other variable characteristic, 10 is rendered automatic in response to an operating condition, such as the change in effective head or pressure on the turbine.

It is an object of this invention to provide the above described and other related improvements in power systems, and more particularly in 15 hydraulic power systems, and their operation, features of the invention being apparent from the accompanying description and the drawing relative thereto, disclosing an embodiment of this invention, and being more particularly pointed out in the claims herein.

The illustrative showing of the drawing is 20 a diagrammatic showing of a hydro-electric system embodying features of this invention.

In accordance with the disclosure of the drawing, 25 an alternating current generator 1 is connected, through a permanent or releasable clutch connection, to hydraulic turbines 2 and 3, of such different design as to secure most efficient operation under substantially different heads and 30 preferably capable of producing substantially the same power when each is subjected to its normal operating head. 4 indicates a source of direct current voltage for supplying any required variable degree of excitation of the field 35 of the generator 1. The circuit 6, supplied by the generator 1, is connected through a line switch 7, to an alternating current load or distribution system 8.

The turbines 2 and 3 may be of either the Francis 40 type or open runner or propeller type, and they may be controlled wholly as to the water admitted thereto and the power produced thereby may be regulated by guide-vanes and actuating mechanism therefor of suitable conventional type. 45 The adjusting ring or element for the guide-vanes of the turbine 2 has connected thereto an actuating rod 10 for accomplishing the desired actuation or control of the guide-vane mechanism of this turbine, and a like actuating rod 11 is provided for controlling the actuation of the guide-vane mechanism of the turbine 3. Each turbine 50 may be regulated so as to maintain the desired constant speed under variable load conditions by its individual automatic controlling means, the controlling means for the turbine 2 being indicated generally at C₂ and a similar controlling means for the turbine 3 at C₃. As indicated in the drawing, there is present, as shown schematically, a servo-motor M of well known construction, such as is used for controlling the 55 guide-vane openings of turbines. The regulating valve V receives fluid pressure, as indicated at K, and admits same, according to the position of the regulating valve piston V₁, either to a passage K₁ communicating with the front side of the regulating piston M₁ of the servo-motor M, or to a passage K₂ communicating with the rear side of the regulating piston M₁. The desired 60 actuation of the turbine guide-vanes or other controlling means for the turbine A is transmitted from the regulating piston M₁ of the servo-motor M in any suitable well known manner. For convenience, a rod may be provided at the 65 rear side of the piston and passing through a sealed aperture in the rear end wall of the cyl-

inder, this rod being connected through a lever or crank M₂ to the operating rod 10 for the guide-vane actuating mechanism of turbine 2 or the operating rod 11 for the guide-vane actuating mechanism or turbine 3.

The motion of the regulating piston M₁ is 80 transmitted to a relay R. A speed governor P receives its revolutions through a drive T from the turbine shaft and transmits the motion of the shifting collar or stud of the governor to the floating lever V—P—R. As soon as the regulating valve piston V₁ is raised out of its mid position, fluid pressure K reaches the front side K₁ of the regulating piston M₁, moving the latter until the regulating valve piston V₁ is brought back to its former mid position. This is attained by the relay R and the floating lever R—P—V in such a way that the motion to the left of the regulating piston M₁ produces an upward motion of the end R of the floating lever, 85 causing the regulating valve piston V₁ to be lowered after it had first been raised by the speed governor.

By shifting the hand wheel R₂ on the relay rod R₁, it is possible to variably determine the controlled speed of operation of each turbine, 100 although for normal operation, the hand wheel occupies a single definite position on the rod corresponding to that normal speed N which insures the desired frequency of current produced 105 by the generator 1. Likewise, this provision for variably positioning the hand wheel R₂ on the rod R₁ constitutes a means for shutting off the supply of water to each turbine, when it is desired to render either turbine inactive.

The normally contemplated operation of the system disclosed herein includes the operation of the turbine 2 alone while the head on the storage source is between the values H_m and H_a, the 110 operation of both turbines 2 and 3 while the available head is between the values H_a and H_b, and the operation of turbine 3 alone while the available head is between values H_b and H_c, the latter corresponding to the minimum head that is economically utilizable by the turbine 3. The de- 115 sign of the turbine 2 is such that quite efficient operation thereof at the normal operating speed N may be secured while the head occupies any value between H_m and H_a; and the design of the turbine 3 is such as to secure quite efficient 120 operation for any values of the head between the values H_b and H_c.

In the range between the values H_a and H_b, both turbines 2 and 3 operate at reduced efficiency and hence reduced output; but, nevertheless, the two turbines together are capable of producing a required average amount of power corresponding to at least the normal output of either of the turbines under its normal or most efficient operating head. Through this provision, a substantial amount of power can be extracted at a relatively high general or average efficiency from a source of supply whose head is subject to variation over a relatively wide range, and this result may be secured with a relatively 140 small capital investment.

Where the variation in head occurs relatively often or at a relatively rapid rate, it may be desirable that the adjusting wheel R₂ of each turbine be automatically shiftable to its several 145 positions on the rod R₁ corresponding to normal operating speed and to an inactive or inoperative condition. This desired automatic control or operation of the end R of the lever V—P—R may be secured through the use of control ap- 150

paratus of the character illustrated which includes the provision of a float 12 in the head water of the turbine and a float 13 in the tail water of the turbine, with flexible cords or chains connected to each of these floats and suitably guided and passing over pulleys fixed to jack shafts 14, 15, respectively, of a mechanical differential, the floats 12 and 13 being balanced by suitable weights 16 and 17, respectively, connected to the other end of the flexible cords attached to the floats. The mechanical differential gear including the jack shafts 14 and 15, has as its differentially driven element a gear 18 which actuates a geared segment 19 connected to an indicating needle 21 which moves over a scale to give an exact indication of the difference in level between the floats 12 and 13, and hence, the net effective head on the turbine or turbines.

The indicating needle 21 is mounted so as to move over and in engagement with contacts 23 and 24. The contact 23 is so disposed relative to the path of movement of the needle 21 that, while the needle is in engagement with the contact 23, the head on the storage source is between the values H_m and H_b ; and the contact 24 is so disposed relative to the path of the needle 21 that the needle is in engagement with the contact 24 while the head on the storage source is between the values H_a and H_e .

When the needle 21 is in engagement with the contact 23, it closes a circuit through an energizing winding 25 of a reversing switch 26 including bridging elements 27 and 28, these latter serving to establish the operating circuit of a motor 29 for forward and reverse operation, depending upon whether the switch is in its upper closed position, as indicated in the drawing, or in its lower closed position. When the needle 21 is in engagement with the contact 24, a circuit is closed through the energizing winding 31 of a reversing switch 32 having bridging portions 34 and 35 serving to establish the operating circuit of an electric motor 36 for forward or reverse operation, depending upon whether the switch is in its upper or lower closed position, the switch being indicated in the drawing as being in its lower closed position.

It will be noted that during a certain part of the travel of the needle 21, corresponding to an available head on the storage source of a value between H_a and H_b , engagement is made by the needle 21 with both of the contacts 23 and 24, under which circumstances the energizing windings of both reversing switches 26 and 31 are closed and the reversing switches occupy their upper closed positions.

Each of the motors 29 and 36 has its shaft provided with a pinion 52, the same being engageable with a gear 53 attached to the adjusting wheel R_2 on the relay rod R_1 of the controlling means C_2 and C_3 , respectively. In the motor circuit through the switch 26 in its upper position, is located a switch 56 biased to closed position and operable to open position by an electro-magnet having an energizing winding 57; and in the motor circuit closed through the switch 26 in its lower position, there is disposed a switch 58 biased to closed position and operable to open position by an electro-magnet having an energizing winding 59. The circuit of the energizing winding 57 is completed through a switch 61; and the circuit through the energizing winding 59 is completed through a switch 63.

A portion of the adjusting wheel R_2 is provided with a projection or flange 67 adapted, through

the reciprocation of the wheel or nut on the relay rod R_1 , to actuate the switches 61 and 63 to closed position, these switches being assumed to be biased to open position. However, this operating means may include a loose connection or portion between the element 67 and the several switches, which insures positive operation of these switches to both open and closed position; and these switches 61 and 63 may be of the snap-operated type. The preferable means for connecting the end of the lever $V-P-R$ to the adjusting wheel R_2 includes a sleeve 68 held between flanges on the rotatable adjusting wheel proper, this sleeve being held against rotation in any suitable manner and having the end of the lever connected to this non-rotatable sleeve. The switch-actuating projection 67 is preferably mounted on the sleeve 68.

In the circuit of the motor 36 when closed through the switch 32 in its upper position, there is provided a switch 71 biased to closed position and actuatable to open position, as indicated, by an electro-magnet having an energizing winding 72; and in the motor circuit closed through the switch 32 in its lower position, there is provided a switch 73 biased to closed position, as indicated, and actuatable to open position by an electro-magnet having an energizing winding 74. The circuit of the energizing windings 72 and 74 are closed by switches 61 and 62, respectively, both biased to open position and moved to closed position by the actuating projection 67 associated with the hand wheel R_2 associated with speed controlling mechanism of the turbine 3, when such hand wheel reaches its predetermined limiting positions corresponding to the normal operating speed N and an inactive or inoperative condition of the turbine 3, such switch-actuating and control mechanism being similar in structure and function to the correspondingly designated parts of the control mechanism of the turbine 2 described hereinabove.

With an available head on the storage source between the values H_m and H_a , as indicated in the illustrative disclosure, the turbine 2 is operative to drive the generator 1, the turbine 3 at this time being inoperative, having been rendered so through the actuation of the guide-vanes or other inlet regulating device to closed position by its controlling means C_3 , the hand wheel R_2 of which is moved to its lowest position by the electric motor 36. This operating condition continues while the available head on the storage source remains above the value H_a , corresponding to the lower limit at which a substantial load can be efficiently supplied by the generator 1 when driven by the turbine 2 alone. On reaching the head value corresponding to H_a , the needle 21, while maintaining engagement with the contact 23, now also makes engagement with the contact 24. Through this latter engagement, wherein it completes the energizing circuit of the winding 31, the reversing switch 32 is actuated to its upper closed position. With the switch 32 in its upper closed position, the limit switch 63 of the regulator C_3 being closed and the limit switch 61 of this regulator being open, and hence the switch 71 being closed, at this time, the motor 36 operates in a direction to cause such actuation of the controlling means C_3 as includes moving the adjusting nut or hand wheel R_2 upwardly upon the relay rod R_1 , to a position wherein it actuates the switch 61 to closed position, thus causing opening of the switch 71 and stoppage

of the motor 36, this position of the hand wheel R_2 corresponding to that setting of the end R of the lever $V-P-R$ which corresponds with the normal speed of operation of the turbine and generator 1. With this condition existing, the turbine 3 assumes a portion of the load and thus assists in driving the generator 1. At this time, each of the turbines 2, 3 continues to supply a proportionate share of the variable load, the turbines being controlled by their individual speed regulating mechanism.

If the available head on the storage source continues to drop to a value corresponding to H_b , the indicating needle at this time breaks engagement with the contact 23, thus deenergizing the winding 25 and permitting reversing switch 25 to drop to its lower closed position wherein the operating circuit of the motor 29 is closed to produce operation of the latter in a reverse direction. The effect of this operation on the controlling means C_2 of the turbine 2 is to shift the adjustable hand wheel R_2 downwardly upon its relay rod R_1 to a position corresponding to an inactive condition of the turbine 2 wherein the guide-vanes or other inlet controlling means are closed. As the adjustable hand wheel R_2 reaches its lower limiting position corresponding to a rendering of the turbine 2 inactive, the limit switch 63 operatively associated with the hand wheel R_2 is moved to closed position wherein it energizes the winding 59 causing opening of the switch 58 in the motor circuit and consequent stoppage of the same.

Under these conditions, the turbine 3 is alone effective to drive the generator 1; and this condition exists while the available head on the storage source remains above the value H_c . As has been described hereinabove the turbine 3 is designed and operative to drive the generator 1 at normal operating speed under an average available head between the values H_b and H_c , to thereby produce power at maximum efficiency. It is presumed that the value H_c is predetermined at such a value as will produce reasonably efficient operation of the turbine 3. When the available head drops below such a lower limiting value, the indicating needle 21 moves from engagement with the contact 24 and thus, through deenergization of the winding 31 of the reversing switch 32, causes operation of the motor 36 in a reverse direction, to thereby cause such actuation of the controlling means C_3 of the turbine 3 as provides for shifting of the hand wheel R_2 downwardly on its relay rod R_1 to cause closure of the guide vanes or other inlet controlling means and consequent cessation of operation of the turbine 3 and the generator 1, ordinary low-voltage responsive devices being provided, if desired, to insure disconnection of the generator from the live circuit.

It will be apparent that as the available head on the storage source again rises through the several values H_c , H_b and H_a reverse operations occur, as will be apparent from the description hereinabove, in an order which first renders the turbine 3 operative to drive the generator 1, then renders the turbine 2 operative to assist the turbine 3 as the head reaches the value H_b , and, as the head reaches the value H_a , causes the turbine 3 to be rendered inactive, the turbine 2 alone continuing to furnish the power required for the operation of the generator 1.

With the above described arrangement of the hydraulic and electrical features of the installation which permits transferring the load or power

required for operating the generator from one to the other of the turbines which are of such individual design and capacity as to efficiently supply the required power throughout the total variation in head, the amount of water used per horsepower developed is reduced, and the available water is economically and efficiently used; and the capital investment involved in the installation is made to pay an increased return.

While the hydro-electric unit described above finds great utility when connected with a distribution system whose frequency is definitely established by means other than this particular unit, nevertheless, it finds considerable utility when it is the only power unit connected to or establishing the frequency of the distribution circuit.

It should be understood that the invention claimed is not limited to the exact details of construction and design or the embodiment or use shown or described herein, for various modifications and other embodiments and uses of the invention will be apparent to persons skilled in the art.

It is claimed and desired to secure by Letters Patent:

1. A hydraulic power unit for operation under conditions of variable effective head, comprising a plurality of hydraulic turbines designed for most efficient operation under different heads, a power translating unit operatively connectible to said turbines to be driven thereby, regulating means operatively associated with said turbines for causing either one alone or both of said turbines to effectively drive said power translating unit, and means automatically responsive to the energy available at the turbine inlet for controlling said regulating means.

2. In combination, a power unit comprising a plurality of fluid driven prime movers subject to operation under widely varying fluid heads, a power translating device arranged to be driven by either of said prime movers, and governing means including instrumentalities responsive to the available fluid head on said prime movers for insuring operation of said translating device by one or the other of said prime movers.

3. In a power system, a plurality of hydraulic turbines, a machine arranged to be driven thereby, means for regulating the admission of water to said turbines, speed responsive governing means for controlling the speed of said turbines to insure operation thereof at one predetermined speed under normal running conditions, and means responsive to the effective head on said turbines for adjusting said governing means to cause the latter to insure controlled operation of said driven machine by one or the other of said turbines alone depending upon the value of said effective head.

4. In a power system, a plurality of hydraulic turbines, a power translating unit arranged to be driven thereby, means for regulating the admission of water to said turbines, speed responsive governing means for controlling the speed of said turbines to insure operation thereof at a predetermined speed under normal running conditions, and means responsive to the effective head on said turbines for adjusting said governing means to cause the latter to insure controlled operation of said power translating unit by one or the other of said turbines alone or both of said turbines.

5. A hydraulic power installation, comprising a plurality of hydraulic turbines designed for most efficient operation under different heads and subject to a variable available supply of water, a

- power translating unit arranged to be driven by either one of said turbines, controlling means for said turbines operative to maintain a predetermined characteristic of the power output of 5 said translating unit under conditions of variable load thereon, and means automatically responsive to a characteristic of the available head on said turbines for providing for effective operation of said translating unit by either one of said 10 turbines alone. 6. A power installation comprising a plurality of hydraulic turbines designed for most efficient operation under widely different heads and subject to a variable available supply of water, a 15 power translating unit arranged to be driven by either or both of said turbines, and means responsive to a characteristic of the available supply of water for determining which of said turbines is in effective power supplying relation to 20 said translating device, whereby the efficiency of operation of said installation is sustained to an increased degree in spite of operation of said turbines under variable heads. 7. In combination, a power unit comprising a 25 plurality of hydraulic turbines subject to operation from a storage source of widely varying head, a power translating device arranged to be driven by said turbines, and governing means including instrumentalities responsive to a condition attendant upon the operation of said unit for insuring operation of said translating device by either one alone or both of said turbines. 8. In a power system, a plurality of hydraulic 30 turbines supplied from a storage source of widely varying head, a power translating unit arranged to be driven by said turbines, means for regulating the admission of water to said turbines speed responsive governing means for controlling the speed of said turbines to insure operation thereof at a predetermined speed under variable load conditions, and means responsive to the effective head on said turbines for adjusting said governing means to cause the latter to insure the effective operation of said power translating unit by one or the other of said turbines alone or 45 both turbines together determined by the available head of said storage source. 9. A power installation, comprising a plurality of hydraulic turbines subject to operation under a widely varying range of head thereon, a machine arranged to be driven by one or the other or both of said turbines, and means independent of the load on said machine and responsive to said head for causing said machine to be effectively driven by either one alone or both of said turbines depending upon the available head thereon to thereby increase the degree to which the efficiency of said power installation is sustained throughout said range of variation in the 50 head to which said turbines are subjected. 10. A power installation for operation under conditions of widely varying head, comprising a plurality of hydraulic machines each designed for most efficient operation under a head different from that for which the other is designed, a power translating unit arranged to be driven by either of said hydraulic machines, a power system connected to said power translating unit a characteristic of whose operation is established by means other than said power translating unit, and instrumentalities automatically controlled in response to the available head to which said hydraulic machines are subjected for insuring 55 under certain conditions the transfer of energy 60 65 70 75
- between said power system and said power translating unit with only that one of said hydraulic machines in effective operation which operates with the greater efficiency under the head available at the time. 11. The method of operating a power installation comprising a plurality of prime movers operable from a source of fluid energy of variable available energy supply and each designed for most efficient operation under different conditions from the other as to available energy supply at said source and arranged to drive a common load, which comprises utilizing as the effective source of power for said load that one of said prime movers which is designed for more efficient operation under the condition of available energy supply existing at the particular time, and changing from one to another of said prime movers for the effective source of power for said load as the said condition of available energy supply varies. 12. Method of operating a hydraulic power installation comprising a plurality of hydraulic turbines operable from a fluid supply under variable head and each turbine designed for most efficient operation under a head value different from the other turbine and said turbines being arranged to supply energy to a common load, which comprises utilizing as the effective source of energy for said load that one of said turbines whose most efficient operating head more closely approximates the head available for the turbines, and changing from one to another of said turbines as the effective source of energy for said common load as the head on said fluid supply approaches the most efficient operating heads of the several turbines. 13. In a hydraulic power installation, the combination of a plurality of hydraulic turbines subject to operation under varying values of available head, means for converting the energy of said turbines and supplying said energy to a common load, and controlling means for said turbines responsive to the available head thereon for insuring that the turbine capable of operation with greater efficiency at a particular value of available head supplies under such value of head a greater proportion of its full load than the other turbine. 14. In a power installation, the combination of a plurality of fluid-operated prime movers subject to operation under varying values of inlet pressure, means for transmitting the energy of both of said prime movers to a common load, and controlling means for said prime movers responsive to the available supply of energy for said prime movers for insuring operation of one or the other or both of said prime movers depending upon the value of said inlet pressure. 15. In a power installation, the combination of a plurality of fluid-operated prime movers each designed for most efficient operation under a different degree of inlet pressure from the other and subject to operation from a source of fluid energy of variable available pressure, and controlling means for said prime movers including means responsive to the available pressure of said energy source and operative under certain pressure conditions to cause only that one of said prime movers to be effective for power-supplying purposes which operates more efficiently under the available inlet pressure. 125 130 135 140 145
